UNITED STATES PATENT OFFICE.

WILLIAM H. DOYLE, OF PHILADELPHIA, PENNSYLVANIA, ASSIGNOR TO PHILADELPHIA LODGE NO. 2 BENEVOLENT AND PROTECTIVE ORDER OF ELKS, OF PHILADELPHIA, PENNSYLVANIA, A CORPORATION OF PENNSYLVANIA.

DESIGN FOR A BADGE.

No. 39,849.

Specification for Design.

Patented March 2, 1909.

Application filed December 28, 1908. Serial No. 469,732. Term of patent 7 years.

To all whom it may concern:

Be it known that I, WILLIAM H. DOYLE, a citizen of the United States, residing in the city and county of Philadelphia, State of Pennsylvania, have invented a new, original, and ornamental Design for a Badge, of which the following is a specification, reference being had to the accompanying drawing, forming part thereof.

The figure is a view of a badge showing my novel design.

I claim:

The ornamental design for a badge, as shown.

WM. H. DOYLE.
